(57) CLAIM

The ornamental design for an ashtray and saucer assembly, as shown.

DESCRIPTION

FIG. 1 is a left perspective view of the ashtray and saucer assembly;

FIG. 2 is a right perspective view thereof;

FIG. 3 is a top view thereof;

FIG. 4 is a bottom view thereof;

FIG. 5 is a left side view thereof;

FIG. 6 is a right side view thereof; and,

FIG. 7 is an exploded view of the ashtray and saucer assembly.

The broken lines in the drawings depict portions of the ashtray and saucer assembly that form no part of the claimed design.
